UNITED STATES PATENT OFFICE

2,191,899

UNIVERSAL SHARPENER

Adam Primak, Milwaukee, Wis.

Application September 7, 1937, Serial No. 162,717

3 Claims. (Cl. 51—69)

This invention appertains to sharpening devices of a universal character capable of operating upon a number of different kinds of implements, such as scissors, knives, saws, ice skates, and the like.

One of the primary objects of my invention is to provide a sharpening device embodying a novel rest or clamp for the work, so that knives, scissors, etc., can be conveniently held thereon and retained in the desired position best suited for engagement by the abrading or sharpening member.

Another salient object of my invention is to provide a rest in which scissors and the like can be conveniently clamped on one face thereof, and knife blades on another face thereof.

A further object of my invention is to provide novel means for mounting the abrading member on the device, whereby the member can not only be readily operated at different angles and heights to correspond with the body of the cutting edge of the scissors or other implements on the rest, but can also be advanced across the length of a blade, thereby rendering the device applicable for correctly sharpening the teeth of saws.

A further important object of my invention is to provide novel means for reciprocally mounting the abrading or sharpening member on a guide rod rockably supported by a traveling nut on a feed screw, whereby the desired adjustments can be obtained and the sharpening quickly accomplished.

A still further object of my invention is to provide a sharpening device of the above character, which will be durable and efficient in use, one that will be simple and easy to manufacture, and one which can be placed upon the market at a reasonable cost.

With these and other objects in view the invention consists in the novel construction, arrangement, and formation of parts, as will be hereinafter more specifically described, claimed, and illustrated in the accompanying drawings, in which drawings:

Figure 1 is a top plan view of my improved sharpening device, showing parts thereof broken away and in section to illustrate structural details.

Figure 2 is a side elevation of the device, with parts thereof broken away and in section, the clamp for the scissors being shown in its released position.

Figure 3 is a detail section taken on the line 3—3 of Figure 2, looking in the direction of the arrows, illustrating the clamp and adjustment for the scissors.

Figure 4 is a detail fragmentary view through the implement rest, illustrating the clamp for the knife blade.

Figure 5 is a detail fragmentary view illustrating a modified form of guide rod for the reciprocating abrading member, which can be mounted in different position on the device.

Figure 6 is a detail section taken on the line 6—6 of Figure 1, looking in the direction of the arrows, illustrating the adjustment for the guide rod.

Figure 7 is a detail section taken on the line 7—7 of Figure 2, looking in the direction of the arrows.

Figure 8 is a view similar to Figure 3, showing a scissor or shear blade in dotted lines, held on the implement rest.

Figure 9 is a transverse section through the abrading member, taken on the line 9—9 of Figure 2, looking in the direction of the arrows.

Figure 10 is a detail section taken on the line 10—10 of Figure 1, looking in the direction of the arrows, illustrating the position of the traveling nut, which is used for rockably supporting the guide rod.

Referring to the drawings in detail, wherein similar reference characters designate corresponding parts throughout the several views, the letter D generally indicates my improved sharpening device, which includes an upright post 15 formed on a supporting base 16, which can be of any desired form. The upper end of the post 15 has secured thereto or formed thereon the rest 30 for the implements to be sharpened. This rest embodies a head 17 having a horizontally disposed body portion 18 and a depending vertically disposed flange 19. The lower edge of the flange 19 has in turn formed thereon the outwardly extending seat or rib 20, which is provided with a plurality of threaded openings 21 for the reception of supporting screws 22, the purpose of which will be hereinafter more fully set forth.

The upper face of the body portion 18 is utilized 40 for supporting knife blades to be sharpened, while the flange 19 and its rib 20 form a support for scissors, saws, and the like, which are to be sharpened.

Arranged upon the upper face of the body portion 18 is a horizontally extending clamping jaw 23 for the knife blades, and this jaw has formed thereon a depending tail-piece 24 received in a slot in the body portion of the rest. The tail-piece intermediate its ends is rockably mounted 50 upon a pivot pin 25 carried by the rest, and an adjustment screw 26 is carried by the rest for engaging the lower end of the tail-piece, whereby the tail-piece can be rocked, so as to move the jaw 23 into its clamping position relative to the 55 top face of the body portion 18.

A clamping jaw 27 is provided for engaging the implements which are to be clamped in a vertical plane against the flange 19, and this jaw is also provided with a depending tail-piece 28, 60

which is received in a slot 29 formed in the rib 20. An adjusting screw 30 is carried by the post 15 and bears against the lower end of the tail-piece 28, whereby the jaw 27 can be brought into 5 its clamping position relative to the work. The work is adapted to be supported by the screws 22, and, obviously, these screws can be raised and lowered relative to one another, so that the work can be supported in the desired position.

10 Firmed on or secured to the post 15 below the work rest is an outwardly extending arm 31, the outer end of which in turn has formed thereon the upwardly extended, right-angularly disposed, threaded standard 32. If desired, the arm 31 can 15 be braced adjacent to its outer end by a depending leg 33. This leg can be provided with any preferred type of foot 34 for engaging the surface on which the sharpening device is placed.

Threaded upon the standard 32 is an adjustable 20 block 35, having formed thereon the laterally extending bracket 36. The outer end of the bracket 36 has formed thereon a bearing ear 37 for receiving one end of a feed screw 38, which extends longitudinally of the bracket. This feed screw 25 rotatably extends through a smooth opening formed in the block 35, and the feed screw has formed thereon or secured thereto a manipulating crank 39, whereby the feed screw can be readily turned.

30 In order to prevent longitudinal movement of the feed screw in the block 35, the block carries a holding screw 40, which is adapted to engage in an annular groove 41 formed in the feed screw. To hold the block against turning movement on 35 the standard 32 after the adjustment of the block, the block carries a thumb-screw 42, which is adapted to contact with the standard 32.

Mounted upon the feed screw 38 is a traveling nut 43 having formed thereon a pair of spaced 40 outstanding ears 44. The guide rod 45 for the abrading member 46 is received between the ears 44 and rockably mounted thereon by a pivot pin 47. Obviously, by rotating the feed screw the traveling nut can be fed longitudinally of the 45 bracket and longitudinally of the implement rest.

The abrading member 46 includes a longitudinally extending sleeve 48 having formed on its inner end a clamping block 49. The opposite end of the sleeve terminates in a threaded shank 50 50 on which is adjustably mounted the manipulating handle 51. Slidably mounted upon the sleeve 48 is an adjustable clamping block 52, and a file 53 and a sharpening stone 54 are adapted to be clamped between the blocks 49 and 52 on opposite 55 sides of the sleeve 48.

By turning the handle 51, the same can be brought into contact with the block 52, so that the block can be moved into its gripping position with the file and stone. Obviously, the file and stone 60 can be of any desired character.

In use of my improved device, the abrading tool is placed on the guide rod 45 and turned on the guide rod, so as to bring either the file or the stone into correct position for engaging the implement to be sharpened. The abrading member can be reciprocated on the guide rod, so that the file or stone can be brought across the scissor or knife edge, as the case may be.

When scissors or other like implements are to 70 be sharpened, the same are placed on the screws 22, and the screws are adjusted to bring the cut-

ting edge into the desired position above the top face of the implement rest, after which the screw 30 is manipulated to bring the jaw 27 into gripping contact with the blade.

The block 35 is now raised or lowered so that the abrading implement will be disposed at the desired angle, and the feed screw can be rotated so that the feed nut will be arranged at the best desired position for supporting the abrading member. 10

The abrading member can now be reciprocated and swung on the pivot pin 47, as heretofore described.

When a knife is to be sharpened, the same is laid on the top face of the body portion 18 of the 15 rest under the jaw 23, and when the blade is disposed in the correct position the jaw 23 is moved into its clamping position therewith. After the desired adjustment of the abrading member, the abrading member is reciprocated back and forth 20 over the cutting edge.

When saws are to be sharpened, a triangular file (not shown) can be substituted for the flat file 53, and after a tooth has been sharpened the screw can be given a turn, so as to advance the 25 traveling nut the distance of one tooth, so that the next saw tooth can be correctly sharpened.

In some instances, the block 35 with its bracket and feed screw can be removed from the standard 32, and the traveling nut 43 can be threaded 30 directly on the standard 32.

In Figure 5 I have shown a nut 54 threaded directly on the standard 32, and, if desired, a guide rod 55 for the abrading member can be connected to the nut, having a stop 56 on its inner end for engaging the nut, so that swinging movement of the guide rod in one direction will be limited. 35

Changes in details may be made without departing from the spirit or the scope of my invention, but what I claim as new is:

1. A manually operated sharpening device comprising, a clamp for the implement to be sharpened, a feed screw extending in spaced parallel relation to the clamp, a traveling nut on the feed screw, a guide rod rockably secured to the nut, and an abrading member reciprocally mounted on the guide rod. 40

2. A manually operated sharpening device comprising, a clamp for the implement to be sharpened, a vertically disposed threaded standard arranged in advance of the clamp, a block adjustably mounted on the standard, a laterally extending feed screw rotatably carried by the block and disposed in substantial parallel relation to the clamp, a traveling nut on the feed screw, and a reciprocating abrading member rockably connected to the nut. 45

3. A manually operated sharpening device comprising, a post, a base on the lower end of the post, a tool rest on the upper end of the post, 50 clamps carried by the rest, an outwardly extending arm carried by the post, an upstanding, vertically disposed threaded standard on the arm, a block adjustably mounted on the standard, a feed screw rotatably carried by the block and disposed in substantial parallel relation to the tool rest, a traveling nut on the feed screw, a guide rod rockably connected to the nut, and an abrading member 55 slidably mounted on the guide rod.
